UNITED STATES PATENT OFFICE.

JAY B. RHODES, OF KALAMAZOO, MICHIGAN.

DISPENSING CAN.

1,403,636.

Specification of Letters Patent. Patented Jan. 17, 1922.

Application filed December 27, 1920. Serial No. 433,262.

To all whom it may concern:

Be it known that I, JAY B. RHODES, a citizen of the United States, residing at Kalamazoo, county of Kalamazoo, State of Michigan, have invented certain new and useful Improvements in Dispensing Cans, of which the following is a specification.

This invention relates to improvements in dispensing cans.

10 My improved dispensing can is especially designed by me for the handling of lubricants such as in the sale of lubricants to motorists where the lubricant is poured into the crank case or lubricant receptacle of an automobile.

The main objects of this invention are: First, to provide an improved dispensing can by means of which lubricant may be conveniently discharged into the crank case or 20 other lubricant receptacle of a motor vehicle at a rate permitting it to pass through the screened intake and without dripping on the floor or vehicle, and further without soiling the hands of the person manipulating the 25 same, and the effective avoidance of clog or drip at the vent.

Second, to provide a dispensing can in which an ordinary "Mason" fruit jar may be used as the receptacle or container, the contents being visible within the receptacle.

Third, to provide an improved dispensing can which may be filled by means of a measuring pump without removing the cap.

Further objects, and objects relating to 35 structural details, will definitely appear from the detailed description to follow.

I accomplish the objects of my invention by the devices and means described in the following specification. The invention is 40 clearly defined and pointed out in the claims.

A structure which is the preferred embodiment of my invention is clearly illustrated in the accompanying drawing forming a part of this specification, in which:

45 Fig. I is a side view of my improved dispensing can with the parts broken away and vertically sectioned to show structural details.

Fig. II is a detail view illustrating the 50 manner of using the can.

Fig. III is a detail view, showing the can completely inverted.

In the drawing similar reference characters refer to similar parts throughout the 55 several views.

Referring to the drawing the measuring

receptacle 1 is preferably of glass, a fruit jar of the well known "Mason" type being very satisfactory.

I provide a dome shaped cap 2 having a 60 central discharge and filling spout 3. The cap is threaded upon the receptacle although it is not necessary to remove it in order to fill the receptacle.

It is usual in dispensing lubricants to 65 motorists to measure the lubricant by means of a measuring pump. The spout of the pump may discharge into the spout 3.

I provide a vent tube 4 which is disposed at the side of the spout 3 with its lower end 70 depending into the cap but terminating above the normal liquid level 5; that is when the receptacle contains its normal amount of liquid, say one quart, the level of the liquid is below the vent. 75

The upper end 6 of the vent tube is beveled or inclined so that the operator may conveniently place his finger over the tube and thereby control the passage of air into the container which controls the discharge of 80 the lubricant therefrom. This is particularly desirable when a thick lubricant is dispensed or when the lubricant is thickened by low temperature, as such lubricant does not pass freely through the screens usually present in the lubricant intakes of motor vehicles. 85

By arranging the vent as has been described, the lubricant passes freely into the container through the comparatively small 90 spout and is freely discharged, the air passing out and in as the lubricant enters or is poured from the can.

When the receptacle is inverted, the air flows in at the vent and as the liquid lowers 95 to a point below the inner end of the vent tube the air carries any liquid in the tube neck into the can and it flows out the spout, thus preventing any dripping from the vent.

My improved dispensing can is very convenient to use. The lubricant flows freely from the spout even when the lubricant is quite thick, and further, with reasonable care in filling the can its exterior may be kept free from lubricant as the lubricant 100 does not drip from the vent spout.

Having thus described my invention, what I claim as new and desire to secure by Letters Patent, is:

1. A dispensing can comprising a receptacle, a dome shaped cap threaded upon said receptacle and having a spout at the top, 110

- thereof, said spout being of such diameter as to permit filling of the receptacle therethrough, as by means of a measuring pump, and a vent tube disposed at the front side 5 of said spout and depending into the cap with its lower end above the normal liquid level of said receptacle, the upper end of said vent tube being beveled to facilitate fingering, to control the passage of air there- 10 through.
2. A dispensing can comprising a receptacle, a dome shaped cap threaded upon said receptacle and having a central spout, said spout being of such diameter as to permit the filling of the receptacle therethrough, and a vent tube disposed at the side of said spout and depending into the cap with its lower end above the normal liquid level of 15 said receptacle.
3. A dispensing can comprising a measuring container provided with a dome-shaped top having a central spout, said spout being of such diameter as to permit the filling of the receptacle therethrough, and a 20 vent tube disposed at the front side of said spout and depending into the top with its lower end above the normal liquid level of said container.
4. A dispensing can comprising a receptacle, a cap therefor having a spout, said spout being of such diameter as to permit the filling of the receptacle therethrough without removing the cap from the receptacle, and a vent tube disposed on the outside of said spout with its lower end projecting into the cap but above the normal liquid level thereof, the outer end of said vent being positioned so that the finger of the operator may be placed over the same to control the admission of air therethrough. 25 30 35 40

In witness whereof, I have hereunto set my hand and seal in the presence of two witnesses:

JAY B. RHODES. [L.S.]

Witnesses:

LUELLA G. GREENFIELD,
MARGARET L. GLASGOW.
